SPACE CONDITION RESPONSIVE INSTRUMENT

Grover M. Russell and Carlos B. Morgan, both of Goshen, Ind., assignors to Penn Controls, Inc., Goshen, Ind., a corporation of Indiana

Filed June 14, 1965, Ser. No. 85,700

Term of patent 14 years

(Cl. D52—7)

FIG. 1

FIG. 2

FIG. 1 is a bottom perspective view of a space condition responsive instrument embodying our new design; and FIG. 2 is a top perspective view thereof.

The essential features of the design reside in the portions shown in solid outline.

We claim:

The ornamental design for a space condition responsive instrument, substantially as shown and described.
